REISSUED

UNITED STATES PATENT OFFICE

120,924

DESIGN FOR A PORTABLE LIGHTING FIXTURE

Clarence L. Steber, Oak Park, Ill.

Application February 12, 1940, Serial No. 90,217

Term of patent 7 years

To all whom it may concern:

Be it known that I, Clarence L. Steber, a citizen of the United States, residing at Oak Park, Cook County, Illinois, have invented a new, original, and ornamental Design for a Portable Lighting Fixture, of which the following is a specification, reference being had to the accompanying drawing, forming part thereof.

The figure is a perspective view of a portable lighting fixture, showing my new design.

I claim:

The ornamental design for a portable lighting fixture, as shown.

CLARENCE L. STEBER.
